Charles C Clark.
INVENTOR.

UNITED STATES PATENT OFFICE.

CHARLES C. CLARK, OF DAVENPORT, IOWA.

GAS-BURNER DEFLECTOR.

Application filed July 6, 1928. Serial No. 290,815.

The object of this invention is to provide an improved auxiliary gas burner or flame deflector, adapted to be placed above or upon the standard gas burner of stoves, heaters or furnaces.

Another object is to provide an improved burner whereby the gas after leaving the regular burner is permitted to combine with such quantities of oxygen as will form a mixture capable of giving the maximum heat content upon combustion.

Further objects are to so construct the burner of a convexo-concavo configuration as to cause the flame to be concentrated upon the article to be heated, to increase the amount of air or oxygen which is consumed with the gas, to reduce the time required to heat an article and to furnish a device which retains the heat after the flame has been extinguished.

The primary object of this invention is to construct the flame deflector with radial segments forming passageways whereby the gas and air are admixed and conducted to the orifices in the proper proportion for correct combustion, thereby obtaining more heat units.

The improvements may be more readily understood by reference to the drawing wherein:

Fig. 1 is a plan view of the cap.

Fig. 2 is a section taken on the line 2—2 of Fig. 1 showing the convexo-concavo configuration.

Fig. 3 is a section taken on the line 3—3 of Fig. 1.

The burner or cap may be cast or stamped from metal such as iron, aluminum, copper, brass or any suitable material which will withstand the heating and cooling temperature encountered. The body of the device designated by the numeral 10 is of general convexo-concavo outline; it has been found from an exhaustive trial of devices of this type that the convexo-concavo outline is superior to that of a truncated cone or of a flat

type burner. The body 10 is provided with alternately raised and lowered segments or ribs, 11 and 12. These segments form radially disposed passageways 13 whereby as the gas leaves the regular burner it is conducted to the orifices 14 or 15. The convexo-concavo outline of the burner causes the gas to travel

in whirling eddies, thereby sucking in the maximum amount of air thru the openings 16. These openings 16 are provided due to the raised segments 11 which continue to the very edge of the burner.

The creation of these eddies gives a steady flow of combustive material to the orifices and prevents the setting up of cross currents due to the stream of gas from the burner striking the cap at too sharp an angle.

The lowered ribs 12 permit the making of the cap with a minimum weight of material and allow a uniform thickness to be maintained so that in heating and cooling of the caps it will not break or warp due to internal stresses.

The side orifices 14 are arranged about midway up the body 10 and centrally disposed in the ribs 11 and 12. The central orifice 15 is the principal place of combustion and throws an intense stream of heat upon the article.

The formation of the cap with the ribs 12 extending to the outer periphery and all terminating in the same horizontal plane, when the cap is placed upon the burner, permits a cap of the same size to be used upon the various sizes and types of gas burners. These ribs 12 act as a means of maintaining the cap the proper distance above the gas burner to permit the entrance of air into the openings 16. Without these depressed ribs when the cap is placed upon some types of gas burners it settles down close to the burner preventing the entrance of air and causing incomplete combustion of the gas, which in turn results in the giving off of poisonous carbon monoxide.

It is to be understood that the cap may be made in any size or material desired and is adaptable wherever gaseous fuel is burned.

What I claim is:

1. A flame deflector cap for gas burners, including a body portion composed of radially disposed alternately raised and lowered connecting segments, said alternately disposed segments providing radially disposed passageways whereby complete combustion of the gas is facilitated, and an orifice centrally disposed in said body.

2. A gas burner, comprising a convexo-concavo body portion formed of a plurality of alternately raised and lowered radially dis-

posed segments, the raised segments at the periphery of the burner outline an opening for the combustion gases, a central orifice and a plurality of intermediate orifices circumferentially disposed in said raised and lowered segments.

3. In a flame deflector cap for gas burners,

a convexo-concavo body portion, a central orifice, radially disposed alternately raised and lowered segments comprising said body portion, said raised segments providing radially disposed passageways whereby complete combustion of the gases is facilitated.

CHARLES C. CLARK.
